FIG. 3 is a front elevational view of the embodiment shown in FIG. 1;

FIG. 4 is a rear elevational view of the embodiment shown in FIG. 1;

FIG. 5 is a left-side elevational view of the embodiment shown in FIG. 1;

FIG. 6 is a right-side elevational view of the embodiment shown in FIG. 1;

FIG. 7 is a top plan view of the embodiment shown in FIG. 1; and,

FIG. 8 is a bottom plan view of the embodiment shown in FIG. 1.

The broken lines in the drawings depict portions of the vending machine assembly for an autonomous delivery robot that form no part of the claimed design.
